UNITED STATES PATENT OFFICE

138,535

DESIGN FOR AN AIRPLANE

Edward F. Burton, West Los Angeles, and Charles G. Brown, Santa Monica, Calif.

Application September 22, 1942, Serial No. 108,312

Term of patent 14 years

(Cl. D71—1)

To all whom it may concern:

Be it known that we, Edward F. Burton and Charles G. Brown, both citizens of the United States and residents respectively of West Los Angeles, in the county of Los Angeles and State of California, and Santa Monica, in the county of Los Angeles and State of California, have invented a new, original, and ornamental Design for an Airplane, of which the following is a specification, reference being had to the accompanying drawings, forming a part thereof.

Figure 1 is a top perspective view of an airplane showing our new design;

Figure 2 is a bottom perspective view of the airplane in flight, the landing gear thereof being in the retracted position;

Figure 3 is a side elevational view of the airplane depicted in Figures 1 and 2, showing the landing gear in its extended position with dotted lines;

Figure 4 is a top plan view of the airplane depicted in Figures 1, 2, and 3;

Figure 5 is a front elevational view of the airplane of our design with the landing gear being shown with dotted lines in the extended position.

We claim:

The ornamental design for an airplane, substantially as shown.

EDWARD F. BURTON.
CHARLES G. BROWN.
